UNITED STATES PATENT OFFICE.

JOSEPH GUNTHER, OF KANSAS CITY, MISSOURI.

DESIGN FOR A PLATE OR SIMILAR ARTICLE.

55,269.

Specification for Design.

Patented May 25, 1920.

Application filed February 18, 1918. Serial No. 218,007. Term of patent 3½ years.

To all whom it may concern:

Be it known that I, JOSEPH GUNTHER, a citizen of the United States, residing at Kansas City, in the county of Jackson and State of Missouri, have invented a new, original, and ornamental Design for a Plate or Similar Article, of which the following is a specification, reference being had to the accompanying drawing, forming part thereof.

The figure is a plan view of a pie plate showing my new design applied thereto.

I claim:

The ornamental design for a plate or similar article as shown.

JOSEPH GUNTHER.
